US0D1036694S

(12) **United States Design Patent** (10) Patent No.: **US D1,036,694 S**
(45) Date of Patent: ** Jul. 23, 2024

(54) **HOUSING FOR BIOLOGICAL INDICATOR**

(71) Applicant: **STERITEC PRODUCTS MFG. CO., INC.**, Englewood, CO (US)

(72) Inventors: **Adrian Ponce**, Los Angeles, CA (US); **Kok-Hwee Ng**, Irvine, CA (US); **Darshan Yeliyur Siddegowda**, Mission Viejo, CA (US); **Jenna Zimmerman**, Newport Beach, CA (US); **Dat Nguyen**, Rancho Santa Margarita, CA (US); **Mitchell London**, Mission Viejo, CA (US); **Jake Douglas Knickerbocker**, Westminster, CA (US)

(73) Assignee: **STERITEC PRODUCTS MFG. CO., INC.**, Englewood, CO (US)

(**) Term: **15 Years**

(21) Appl. No.: **29/829,416**

(22) Filed: **Mar. 4, 2022**

(57) **CLAIM**

The ornamental design for a housing for biological indicator, as shown and described.

DESCRIPTION

FIG. 1 is a top perspective view of a housing for biological indicator showing our new design;

FIG. 2 is a bottom perspective view thereof;

FIG. 3 is a top plan view thereof;

FIG. 4 is a right side view thereof;

FIG. 5 is a bottom plan view thereof;

FIG. 6 is a left side view thereof;

FIG. 7 is a rear view thereof; and,

FIG. 8 is a front view thereof.

In the drawings, the equal-length broken lines depict portions of the housing for biological indicator that form no part of the claimed design. The dash-dot-dash broken lines immediately adjacent to the shaded areas define the boundaries of the claim.
